UNITED STATES PATENT OFFICE.

ROBERT C. RAHM, OF WYOMISSING BOROUGH, PENNSYLVANIA, ASSIGNEE TO TEXTILE MACHINE WORKS, OF WYOMISSING, PENNSYLVANIA, A CORPORATION OF PENNSYLVANIA.

BRAIDING-MACHINE.

971,403.

Specification of Letters Patent. Patented Sept. 27, 1910.

Application filed November 29, 1909. Serial No. 530,320.

To all whom it may concern:

Be it known that I, ROBERT C. RAHM, a citizen of the United States, and a resident of the borough of Wyomissing, near the city of Reading, in the county of Berks and State of Pennsylvania, have invented certain new and useful Improvements in Braiding-Machines, of which the following is a specification.

10 My invention relates to braiding machines and my particular object is to provide an improved construction which will enable a part only of the carriers that are jointly employed in ordinary braiding, to be separately 15 operated at intervals upon a disconnected section of the common race-way.

The invention is fully described in connection with the accompanying drawing and the novel features are specifically pointed 20 out in the claims.

Figure 1 is a plan view of the main portion of a braiding machine embodying my invention in simple form. Fig. 2 is an elevation of the same. Fig. 3 is a separate sectional view of the clutch device employed. Fig. 4 indicates a form of braid which may be made upon the improved machine indicated.

The carrier race-way indicated in the top 30 plate 1 of the machine illustrated, differs from that of an ordinary braider in the arrangement of a portion thereof in such manner as to permit of a section of said race-way being disconnected, when desired, so as to 35 serve as a sectional course upon which a part of the series of carriers which normally traverse the whole race-way may be separately operated to produce a narrowed portion of braid. In the drawings this separable section of the whole race-way comprises merely the larger intersecting race-circles 2 and 3; and said section is normally connected with the ordinary race-circles 4 of the adjoining portion of the race-way by the 40 race-circles 5 and linking grooves 6 forming in connection with said section race-circle 3 a compound race-circle. The separable section 2, 3 is adapted to be disconnected from the adjoining portion of the race-way by 45 means of a suitably operated switch 10 and a blind switch 11.

The carrier drive mechanism for the complete race-way shown, comprises the usual train of carrier drive-gears 12, 12 for the intermediate race-circles 4, engaging with the

separable-section drive-gears 13, 13 (indicated in Fig. 1 by dotted pitch-circles) through drive-gear 14 linking gears 15, 15, one of which latter is provided with a clutch mechanism hereafter described. A main drive-gear 16 is shown in mesh with one of the drive-gears 13 and a pattern mechanism drive-shaft 17 is driven by the other gear 13 as indicated. 60

The clutch mechanism provided in connection with the linking drive-gear 15 is adapted to connect or disconnect said gear from its separately rotatable toothed portion 15^a, which latter is driven, through gear 14, with the train of gears 12, 12; and it is also 65 adapted to simultaneously unlock or lock said toothed part 15^a to the bottom plate 1^a of the machine so as to stop the rotation of the engaging gears 14 and 12, 12, 12 when desired, while leaving the gear 15 free to 70 rotate. These results are effected as shown by means of the vertically movable clutch rod 20 (see Fig. 3) which carries, first, an arm 21 provided with a pin 22 guided in an aperture in the bottom plate 1^a and adapted 75 to enter a hole 23 in said toothed part 15^a; and second, an arm 25 carrying a rotatable clutch sleeve 26 having a pin 27 guided in an aperture 28 in the gear 15 and adapted to 80 enter another hole 29 in said part 15^a. The 85 clutch rod 20 is raised and lowered as desired by means of a bell-crank 30 (Fig. 2), which is pivoted to a bracket 31 and operated by pattern mechanism through connecting wires 32, 33; a suitable spring-pressed 90 holding means 35, 36 being employed in well known manner as indicated to yieldingly retain the bell-crank in set position. The switch 10 is similarly operated by the pattern mechanism through connecting wires 95 40, 41 attached to a double arm 42 on the switch shaft 43, and retained in set position by similar holding means. The blind switch 11, which is automatically turned by the carriers, co-operates with the switch 10 in well known manner to connect or disconnect the sectional course race-circles 2, 3. 100

The simple form of pattern mechanism shown comprises two pattern-wheels 50, fixed to a shaft 52 arranged in gear with the 105 shaft 17 already referred to; said wheels being provided with spaced projections 53 whereby the connecting wires 54, 55 are operated, in well known manner, to swing the switch 10 and reverse the clutch rod 20 110

at determined intervals, as will be readily understood.

The simple form of braid shown in Fig. 4 is produced upon the particular form of my improved machine herein specifically described, in a manner readily understood by reference to Fig. 1. Here the switches 10, 11 are represented as set so that the race-circles 2, 3 are disconnected from the adjoining race-circles 5, 4, 4, 4 to form a sectional race-way upon which the carriers 60, 60, 60 indicated will be retained in operation while the other carriers 60^a, 60^a, 60^a upon the main portion of the race-way, are at rest; such sectional operation being adapted to produce the narrow-braided loops indicated at 61, Fig. 4. It will be understood that during such operation the clutch-rod 20 is in raised position, as indicated in Figs. 2 and 3, so as to disengage the gear 15 from the separably rotatable part 15^a and lock the latter by means of the locking pin 22 to the bed-plate 1^a. When however the switch 10 and clutch rod 20 are reversely moved by the pattern mechanism, it will be readily seen that the sectional race-circles 2, 3 will be thrown into connection with the main race-circles 5, 4, 4, 4 through the linking grooves 6, 6, and the sectional drive-gears 13, 13 into coöperative connection with the train of gears 15, 14, 12, 12, 12, so that all the carriers will be traversed upon the whole race-way to produce the full width of braid intervening between the loops 61, 61. The length of this narrowed or loop portions of braid (in the present case a "soutache") is determined by the interval of time allowed to elapse before reversing the switch and clutch to reconnect the sectional course with the main course for renewal of the normal operation of the machine, which interval may be varied as desired by the pattern mechanism.

What I claim is:—

45 1. In a braiding machine, a race-way, a

series of coöperating carriers and drive mechanism therefor, switch mechanism for disconnecting at intervals a section of said race-way with certain of said carriers thereon, and controlling means for said drive mechanism whereby the latter carriers only are made to operate during disconnection of said section.

2. In a braiding machine, a race-way, a series of jointly operated carriers and drive mechanism therefor, switch mechanism for disconnecting at intervals a section of said race-way with certain of said carriers thereon, controlling means for said drive mechanism whereby the latter carriers only are made to operate during disconnection of said section, and means for simultaneously operating said switch mechanism and controlling means.

3. In a braiding machine, a race-way, a series of jointly operated carriers and drive mechanism therefor, switch mechanism for disconnecting at intervals a section of said race-way with certain of said carriers thereon, and clutch mechanism whereby the operation of carriers outside of said section is stopped upon disconnection of said section and restarted upon reconnection of the same.

4. In a braiding machine, a race-way, a series of jointly operated carriers and drive mechanism therefor, switch mechanism for disconnecting at intervals a section of said race-way with certain of said carriers thereon, clutch mechanism whereby the operation of carriers outside of said disconnected section is stopped without stopping the operation of the carriers on said section, and pattern mechanism controlling the operation of said switch and clutch mechanisms.

In testimony whereof, I affix my signature, in the presence of two witnesses.

ROBERT C. RAHM.
